METHOD AND APPARATUS FOR PUMPING

Albert G. Bodine, Jr., Burbank, Calif.

Application April 17, 1941, Serial No. 389,030

45 Claims. (Cl. 103—1)

My invention relates to the pumping of fluid from one location to another by use of a fluid column extending between such locations, be they separated horizontally, as in a pipe line, or vertically, as in a well, the pumping being effected by transmission of elastic vibrations. In general, it involves the pumping of a liquid by transmission of energy through wave motion.

It is an object of the invention to provide a novel method and apparatus for efficient pumping of fluid by use of wave energy transmitted from one location to another to effect movement of fluid along a conduit extending between such locations.

Another object is to provide a novel method and apparatus for pumping fluid by means of acoustic energy and which involves the use of elastic vibrations, preferably existing under conditions of approximate resonance, to actuate one or more valve means in step with the undulations.

The invention also contemplates the provision of auxiliary acoustic means to assist movement of the pumped fluid into the column, and it is a further object of the invention to provide a novel method and apparatus useful in this connection, and also to provide a novel acoustic valve means.

Another object is to provide a novel method and apparatus for pumping fluid in which pressure impulses are generated at one location in a fluid column and moved to another location where they are reflected to produce a rarefaction of sufficient intensity to admit fluid to the column.

Still another object is to provide a novel method and apparatus for pumping fluid which involves the transmission of asymmetrical pressure waves or pressure reverberations in which a wave of condensation is not necessarily followed by a wave of rarefaction of equivalent amplitude throughout all portions of the transmission system.

Another object of the invention is to provide a novel method and apparatus for pumping fluid which avoids excessive cavitation and excessive gas liberation by avoidance of high-amplitude waves of rarefaction and by effectively removing liberated gas so as not to interfere with the generation or transmission of the desired wave energy.

Yet another object of the invention is to provide, in one embodiment, a system for generating acoustic vibrations and a fluid discharge means operated in synchronism with the acoustic vibrations to discharge fluid at predetermined parts of the vibration cycle.

Another object of the invention, in one of its aspects, is to provide for the pumping of fluids by generation of elastic vibrations, and in which the fluid is discharged at a point removed from the generating means a distance corresponding to approximately one quarter wave length or odd multiple thereof. In this connection, it is a further object of the invention to remove fluid from the system at a position at or near the zone of maximum velocity variations to obtain a discharge under more nearly constant pressure conditions.

Still another object of the invention is to provide for the pumping of fluids by acoustic transmission of energy through a fluid column, the mean pressure in which is above atmospheric pressure at all sections of the column.

Another object of the invention is to provide a method and apparatus for pumping fluids by means of partial absorption of acoustic vibrations at a point along a fluid column.

Further objects and advantages of the invention will be made evident from the following description, taken in connection with the accompanying drawings, in which:

Figure 1 is a view, partially in section, of one form of my pumping apparatus;

Figure 2 is a cross-sectional view of a part of the acoustic generating means shown in Figure 1;

Figure 3 is a sectional view, taken on the line 3—3 of Figure 2;

Figure 4 is an enlarged vertical sectional view of the acoustic valve shown in Figure 1;

Figure 5 is a horizontal cross-sectional view, taken along the line 5—5 of Figure 4;

Figure 6 is a vertical sectional view of an alternative acoustic valve;

Figure 7 is a view, partially in section, of an alternative fluid discharge means and control means therefor;

Figure 8 is a side elevational view of a portion of the apparatus of Figure 7, viewed from the lines 8—8 of Figure 7;

Figure 9 is a diagrammatic view, partially in section, of an alternative pumping system;

Figure 10 is an enlarged vertical sectional view of the acoustic valve of Figure 9;

Figure 11 is a cross-sectional view, taken along the broken line 11—11 of Figure 10; and

Figure 12 is an enlarged fragmentary view of one ball and seat of the acoustic valve means shown in Figures 9 and 10.

The mode of operation of the invention can best be described with reference to the pumping of fluids from a well. The subsequent description is largely directed thereto by way of example,

without intention of limiting the application to pumping through substantially vertical conduits, as the invention is applicable to pumping systems in which horizontal conduits are employed to transport fluid from one location to another. Further, while the invention will be described with particular reference to the transmission of elastic vibrations through the fluid being pumped, various aspects of the invention are not limited to the manner in which the elastic vibrations are transmitted to the inlet position of the fluid column.

Considering the general problem of lifting water from a well by forces applied near the top of a fluid column extending downward to communicate with the fluid to be pumped, there are three possibilities of accomplishing this. If a piston at the top of the column is pulled upward slowly to reduce the pressure therebeneath, the depth to which pumping can be effected is limited to about 30'. If the piston is pulled upward with extreme rapidity to create a rarefaction wave traveling downward through the column of sufficient intensity to reduce momentarily the hydrostatic pressure in the lower end of the column to a value below that of the surrounding well fluid in order to obtain a flow into the column, water can be pumped from a somewhat greater depth, usually up to about 100'. Water cannot be pumped in this manner from a greater depth because the necessary rarefaction wave, which in this system must be created at the top of the well for subsequent downward transmission, results in cavitation (because of the lesser mean static pressure at the top of the fluid column), the quick upward movement of the piston actually breaking the water by exceeding the tensile strength thereof. The tensile strength of pure water is about 30 atmospheres and any impurities therein, even in small amount, will reduce the tensile strength to about 10 atmospheres. Ordinary well water has a tensile strength in the neighborhood of 4 atmospheres, or somewhat less than 60 lbs./sq. in. Correspondingly, with this system, the limit of depth of pumping is in the neighborhood of 100'.

The third method of pumping, employed in the preferred embodiment of my invention, is not directly concerned with the production of rarefaction waves at the top of the column and the transmission thereof to the bottom of the column for momentary reduction in pressure sufficient to admit fluid. Instead, the present invention contemplates the transmission of positive or condensation waves downward through the column, corresponding negative or rarefaction waves being largely avoided, as by preventing their formation. Correspondingly, the present invention is not concerned with the generation at the top of the well and the transmission through the fluid column of a rarefaction wave of sufficient intensity to reduce the pressure momentarily at the inlet end of the column to a value below the surrounding pressure. Rather, the preferred embodiment contemplates the generation and transmission of an asymmetrical pressure-pulse wave or a wave of pressure reverberation. Pressure impulses delivered to the top of the column move downward therethrough to a reflecting surface, being there reflected to again move upward. The intensity of the reflected pressure wave may be made to approach closely the intensity of the transmitted pressure wave by use of a good reflecting surface. The reflecting of this wave tends to form a rarefaction of an intensity approxi-

mately equal in amplitude to the wave. The rarefaction thus created by the reflection reduces the pressure in the bottom of the column momentarily to a value below the pressure of the surrounding fluid. The amplitude of the rarefaction wave thus created is reduced by such entrance of fluid. Stated in other words, the pressure wave in its reflection creates, at a period of time corresponding to one-half wave cycle after the reflection, a rarefaction which is used to admit fluid, but which is, to a large extent, absorbed by this entrance of fluid so that the rarefaction wave, moving upward through the column and created because of the reflection of the positive wave, is considerably less in amplitude than the transmitted or reflected positive wave.

Most liquids contain occluded gases which are liberated upon violent reduction in pressure. This is true both with respect to water and particularly with respect to oil. It is known that crude oil contains, in dissolved state, substantial amounts of gases. If these are liberated by a reduction in pressure, they will not immediately re-dissolve upon a re-application of the original pressure. Correspondingly, it is desirable not to reduce the pressure on the pumped fluid more than is necessary. In my system, the maintenance of strong rarefaction waves is not necessary and, in fact, means are provided for limiting the degree to which the pressure on the fluid is decreased. Correspondingly, more of the occluded gases can be retained in the fluid and a more solid column can be maintained, this being desirable from the standpoint of wave transmission.

Those principles can be explained further with reference to Figure 1, which discloses a conduit 12 extending downward in a well, not shown, and which, if desired, may comprise a well casing. This conduit encloses a fluid column 13 extending from a first, or lower, location at which is positioned an acoustic valve means 14 to an upper, or second, location adjacent a generating means, indicated generally by the numeral 15. The intake side of the acoustic valve means opens on the fluid to be pumped. The exit side of this acoustic valve means communicates with the lower end of the column through which the pumped fluid rises to be discharged in a manner to be hereinafter explained. The acoustic valve means 14 admits the fluid into the column when an elastic rarefaction of sufficient intensity occurs in the fluid adjacent this valve means.

In the disclosed embodiment, the acoustic valve means 14 comprises a plurality of devices which permit the flow of fluid into the fluid column but which impede or restrict a reverse flow. Such devices may comprise a plurality of check valves associated with a member 16 attached by threads, or other means, to the conduit 12, and which provides a plurality of apertures 17 extending therethrough. Cages 18 are disposed in counter-bored portions of the apertures 17 and provide valve seats 20 adjacent the continuations of the apertures. The cages 18 contain balls 21 of relatively small size, which are freely movable in a vertical direction within the cages 18, and which are adapted, by reason of the force of gravity or of a downwardly-exerted pressure, as at the arrival of a wave of condensation in the fluid column 13, to close against the seats 20. When the balls 21 are in engagement with their seats 20, the valve means 14 will act as a good reflector of any wave of condensation which may travel down the fluid column 13 and impinge upon the

acoustic valve means. If, however, during the elastic vibration of the fluid column 13, the pressure of the fluid just above the valve means 14 is reduced below the pressure of the fluid in the apertures 17, the balls 21 will rise and permit entrance of the fluid into the fluid column within the conduit 12.

While the acoustic valve means 14 may be designed to prevent flow of fluid from the fluid column 13, it is not in all instances essential that the valve close tightly to prevent loss of fluid under a static head. Rather, the dynamic characteristics of the valve means are of importance in the present invention, the valve 14 functioning as a uni-directional acoustic wave transmitter, as will be later described. Figures 4 and 5 show six check valves disposed concentric with a small aperture 17' extending through the member 16. In some instances, another check valve can be disposed in this aperture, if desired, without departing from the spirit of the invention, or this aperture can be left open to assist in the performing of auxiliary functions to be later mentioned.

In any event, it is very desirable to form the acoustic valve means 14 to provide a good reflecting surface for any wave of condensation as it is desired to reflect such a wave violently upward and create a rarefaction at a time corresponding to one half wave cycle thereafter. Correspondingly, it is desirable to use a large number of ball check valves and to leave the intervening area of the flat upper surface of the member 16 for reflection of the wave of condensation. In addition, the cages 18 desirably provide flat upper surfaces presenting reflecting surfaces to such a wave of condensation, and it is desirable that such reflecting surfaces should be disposed in the vicinity of the reflecting surface provided by the intervening surface of the member 16 so that the wave is deflected with a minimum of distortion. If closer correlation in the levels of these surfaces is desired, the embodiment shown in Figure 6 can desirably be used. Here, the intervening surfaces are at the same level as the surfaces provided by the cages 18, these cages being set in counter-sunk cavities 19 to provide for upward movement of entering fluid, this fluid moving through the apertures 17, between the ball-retaining arms of the cages 18, and thence upward between the peripheries of the flat surfaces of these cages and the walls of the counter-sunk cavities.

Either of the embodiments shown in Figure 4 and Figure 6 can be employed to give a good reflection of condensation or pressure waves, or other valve means presenting a relatively flat reflecting surface can be employed. However, it is very desirable that the movable elements be small so that they may oscillate in step with the elastic vibrations. If they are small, it is not always essential to provide flat-topped cages thereabove as the intervening surface of the member 16 will serve as a good reflector. However, it is usually not desirable, particularly at high frequencies, to use a single large ball exposed to the condensation wave because of the absorbing character of the spherical surface when impinged by a condensation wave, such a spherical surface tending to break up the wave into a plurality of smaller waves, which are both out of phase with each other and which are not reflected directly upward along the fluid column.

At the upper end of the fluid column 13 is located the acoustic generator 15, which is adapted

5 to generate acoustic waves or elastic vibrations in this fluid column. Various acoustic generating means can be employed in this connection, the embodiment shown in Figures 1 and 2 showing a piston 25 which reciprocates with a short stroke in a cylinder 26, which may comprise an extension of the conduit 12. The fluid column extends to the face of the piston so that reciprocations thereof exert a greater or lesser pressure upon 10 the fluid column to develop the elastic vibrations, and particularly the pressure impulses or condensation waves which are used in the invention.

The piston 25 is pivotally connected to a connecting rod 27 through a wrist pin 28, and the connecting rod 27 carries at its upper end a journal 30 which encircles eccentric means on a shaft 31 driven by a source of motive power 32 which may be, for example, an engine or electric motor. A flywheel 33 is preferably mounted on the shaft 31 to assure constant angular velocity, and the motive power source 32 is adapted to drive the shaft 31 at a constant, but preferably adjustable, speed of rotation. The shaft 31 is mounted for rotation in bearings 34 and 35 which are supported, respectively, in bearing supports 36 and 37 suitably secured to the conduit 12.

30 The eccentric means encircled by the journal 30 may comprise a turned portion on the shaft 31 of circular cross section and eccentric to the shaft 31, and designated by the numeral 40, together with a bearing member 41 having an outer cylindrical bearing surface fitting the journal 30 and having an eccentric inner cylindrical surface of substantially the same diameter as the portion 40. The member 41 is adapted to be rotated on the member 40 to obtain any selected relative angular orientation and to be held in the selected position. The member 41 is formed with an outwardly-flanged cylindrical portion 42, on the periphery of which are located sockets 43. A flange 45 is attached to the shaft 31 and has an overhanging portion 46 which encloses the flanged portion 42 of the member 41 and which has a plurality of holes 47 adapted to register with the sockets 43. These holes 47 may be partially threaded to accommodate partially-threaded pins 48, which may be screwed into the holes 47 so that their ends will project into the sockets 43 and connect the member 41 for rotation with the shaft. It will be evident that the eccentricity of the eccentric portion of the member 41 may be caused either to add or subtract from the eccentricity of the portion 40 of the shaft 31 by rotating the member 41 relative to the flange member 45. Such adjustment permits change in the stroke of the connecting rod 27 and the piston 25 to conditions existing in different pumping installations and to conditions arising from a change in the character of the liquid pumped. The member 41 may be turned into any of the angles in which one of the sockets 43 registers with one of the holes 47 and, in such position, may be connected for rotation with the shaft 31 by means of one or more of the pins 48.

60 A fluid discharge opening 50 is provided at some point along the conduit 12 connecting with the fluid column 13, and preferably located near the upper end thereof. I may, for example, locate the discharge opening 50 relatively near the generating piston 25, or I may, with advantage, locate the discharge opening a distance from the piston 25 or from any point of substantially greatest pressure variation, equal to approximately one quarter of the wave length of the elastic vibration being generated in the fluid col-

umn 13, or an odd multiple of one quarter wave length, if this discharge opening is to constitute the point of main delivery of fluid from the system. On the other hand, if this discharge opening is disposed at a point of maximum pressure variation and equipped with a spring-loaded valve, the valve can be adjusted to act as a safety valve to relieve any dangerous internal pressure created by transient or excessive resonant conditions in the system, though usually it should not be set to open to cut off the peaks of the repeated pressure waves desirably transmitted to the acoustic valve means for reflection. Regardless of the positioning of the discharge opening 50, as mentioned above, it is preferably closed by a spring-loaded check valve 51, or other suitable acoustic valve means adapted to permit fluid under pressure within the fluid column 13 to discharge through the valve 51. The discharge side of the valve 51 may communicate with a discharge conduit 52. In some instances, if the discharge opening 50 serves as the main fluid discharge and if proper pressure conditions are present in the conduit 52, I may entirely eliminate the valve means for controlling the flow of fluid and simply provide the discharge opening or orifice 50 through which fluid from the column 13 may discharge at any time when the pressure of fluid adjacent the opening 50 is of such value as to result in discharge of fluid therethrough.

In many instances, it is distinctly advantageous to locate the main discharge opening a distance from the piston 25 or from any point of substantially greatest pressure variation, equal to approximately one quarter of the wave length of the elastic vibrations being generated in the fluid column 13, or an odd multiple of one quarter wave length. For example, this relationship may hold with regard to the positioning of the discharge opening 50 shown in Figure 1. The discharge opening may, if desired, be located on a branch conduit diverging from the conduit 12 and communicating therewith. Such a branch conduit is shown in Figure 1 by the numeral 53, and the provision of a spring-loaded valve 54 at or near the quarter wave length point, constructed similar to the valve 51, is often advantageous to maintain a higher mean pressure on the fluid column, which is conducive to better wave transmission. The fluid in the branch conduit 53 will resonate with the main fluid column and the discharge will be at or near a point of maximum velocity variation, thus giving a discharge of much more nearly constant pressure than would be the case if this discharge took place closer to a zone of maximum pressure variation.

Figure 1 discloses also a conduit 55 communicating with the fluid column through a port 56 immediately adjacent the lower face of the piston 25 when in its uppermost position, this conduit including a valve 57. This conduit is useful in priming the system, the piston 25 being brought to its uppermost position, the valve 57 opened, and fluid introduced through the conduit 55 to fill the conduit 12 to such an extent that the fluid column 13 contacts the under face of the piston 25, at which time the valve 57 may be closed partially or completely and the system set into operation. Such a conduit 55 can also be used to discharge the pumped fluid from the column 13 in timed relationship with the generating means 15 as the piston 25 acts as a slide valve,

covering the port 56 in its downward stroke and uncovering this port in its upward stroke.

In operation, the piston 25 moves up and down in a cylinder 26 with approximately simple harmonic motion, the frequency being determined by the speed of the motive power source 32 and the stroke being determined by the eccentricity of the eccentric portion of the member 41 relative to the shaft 31, as explained above. As the piston 25 moves downward or inward, it compresses the fluid in the immediate vicinity thereof and, on its upward or outer stroke, it permits expansion or upward movement of the fluid adjacent thereto. On the downward stroke, therefore, an intense pressure wave or wave of condensation or pressure impulse is created. This pressure wave travels as an elastic disturbance down the fluid column 13 with a velocity corresponding substantially to the velocity of sound in the medium constituting the fluid column. The pressure wave eventually reaches the bottom of the fluid column and is reflected back by the acoustic valve means 14, the reflected wave being a pressure wave or wave of condensation. The reflected wave travels back up the fluid column 13 with the same velocity and eventually arrives at the face of the piston 25, from which it is again reflected downward as a wave of condensation. If the motion of the piston 25 in the time elapsed between the generation of a pressure wave and its return to the piston has been such that, when the returning pressure wave arrives at the piston, this piston will again be generating a pressure wave, the returning wave can join with the newly-generated pressure wave and form a downwardly-directed pressure wave of increased intensity. Under such circumstances, the fluid column 13 can be said to be in acoustic resonance and a large amount of energy can be stored and transmitted in the fluid column. I preferably adjust the frequency of vibration of the piston 25 to maintain a condition of substantial resonance in the fluid column.

The bottom of this fluid column, as determined by the position of the acoustic valve means 14, should be a zone of maximum pressure variation. The length of the fluid column 13 between the piston 25 and the acoustic valve means 14 should be substantially equal to any multiple of one half wave length of the acoustic vibrations generated by the piston 25, if a condition of substantial resonance is to obtain.

It will be evident that, because of the properties of elasticity and inertia of the fluid, there will be a tendency for each positive pressure or condensation pulse at any point in the fluid column to be followed by a condition of rarefaction or decrease in fluid pressure below the mean-pressure value. In order that fluid be admitted through the acoustic valve means 14, it is desirable that the pressure on the exit side be reduced momentarily below the pressure on the entrance side thereof and, as pointed out above, this reduction in pressure is obtained by reflection of a positive or condensation wave reaching the acoustic valve means. The intensity of the rarefaction thus created adjacent the upper end of the acoustic valve means 14 is dependent upon the intensity of the positive pressure wave preceding, the rarefaction being greater for greater intensities of the positive pressure wave. If, therefore, conditions of approximate resonance are established in the fluid column 13, the rarefactions adjacent the valve 14 can easily be made large enough to overcome the static pres-

sure head tending to hold the valve closed and, under such circumstances the valve 14 opens at the time of each rarefaction to permit an increment of fluid to enter the lower end of the column. When the succeeding pressure wave arrives at the acoustic valve 14, the balls 21 are forced against their seats to close the valve and retain in the fluid column the fluid which was taken in during the period of rarefaction. The provision of an open aperture 17' does not substantially change this condition in view of the limited area. It will thus be seen that the balls 21 move in step with the undulations, and that the acoustic vibrations in the fluid column at the valve means are partially absorbed in that the rarefactions are reduced once liquid begins to flow into the column when the valve opens.

My system desirably employs transmitted positive-pressure or condensation waves for actuation of the acoustic valve means, rather than transmitted rarefaction waves. There is, of course, a tendency for the reciprocating piston 25 to establish both condensation and rarefaction waves. However, I prefer to avoid the presence, at the lower end of the piston, of rarefaction waves corresponding in amplitude to the intermediate condensation waves and, in fact, to cancel in large measure such rarefactions by actually admitting fluid to the zone beneath the piston during a portion of the outward movement, as will be later described with reference to Figure 9. This latter expedient can be employed in the embodiment of Figure 1 by delivering fluid under pressure to the conduit 58.

Correspondingly, the pressure waves in the fluid column 13 are usually not symmetrical in my system as the waves of rarefaction in the upper and intermediate sections of the column do not equal in amplitude the waves of condensation. Not only are the waves of rarefaction reduced at the generating means 15, but it will also be apparent that the rarefaction created by reflection of the positive wave by the acoustic valve means is, to a large extent, absorbed by entrance of fluid to the fluid column. Correspondingly, the wave employed in my invention can be asymmetrical, even to an extent of substantially cancelling rarefactions and producing a pressure wave of reverberation.

In the case in which a simple orifice is employed for discharging the fluid from the column, for example the orifice 50, the fluid from the column moves through the orifice whenever the mean pressure of the fluid is greater than the mean pressure in the discharge side of the orifice, or, if the port 58 is utilized for discharge, whenever this port is opened and the internal pressure exceeds the external pressure. When a spring-loaded valve, such as designated by the numerals 51 or 54, is employed, the fluid is discharged whenever the fluid pressure is sufficiently great to overcome the action of the spring and open the valve. In practice, it is desirable to employ a spring-loaded discharge to maintain a considerable mean pressure, often from 25-100 lbs./sq. in., or considerably more, in the conduit 12. In continuous operation of the system, the amount of fluid discharged adjusts itself to equal the amount taken in.

The system thus far described can be employed with the acoustic valve means 14 at the lower end of the conduit 12. However, it is often desirable to dispose the valve at a position above the lower end of the conduit a distance corre-

sponding to substantially one half wave length, while still maintaining this valve adjacent a zone of maximum pressure variation. This is suggested in Figure 1, the lower portion of the conduit being designated by the numeral 12' and being open at its lower end to communicate with the well fluid.

This open-ended conduit 12' constitutes one embodiment of an auxiliary means assisting the pumping action, and particularly the action of the acoustic valve means. The interior of the conduit 12' constitutes an acoustic chamber 58 and forms a part of an acoustic means assisting in the operation of the valve, in a manner which will now be described.

When a wave of condensation reaches and reflects from the acoustic valve means, the rarefaction created one half wave cycle thereafter will be, in part, transmitted through the now-open valves and through the aperture 17' to the fluid in the acoustic chamber 58. This rarefaction will move downward to the open lower end and produce a wave of condensation which travels upward through the fluid in the acoustic chamber to reach the acoustic valve one wave cycle after the rarefaction wave which moves through the acoustic valve means. Correspondingly, this upward-moving pressure wave acts in step with the rarefaction created in the lower end of the fluid column 13 to assist in opening the valves by moving the balls 21 thereof upward. This action can take place irrespective of whether the aperture 17' is open, as shown, or closed by a check valve similar to those shown in Figure 4. If this aperture remains open, a further assisting action is established which is also in proper phase with the wave energy tending to open the valves. In this connection, it will be clear that, if the aperture 17' is open, a minor portion of the condensation wave reaching the acoustic valve 14 will be transmitted to the acoustic chamber 58 and will move downward therein to produce a wave of rarefaction upon discharge from the lower end thereof. This wave of rarefaction will move upward through the fluid in the acoustic chamber 58 to reach the lower portion of the acoustic valve means at the instant when a succeeding condensation wave reaches the upper portion of the acoustic valve through the fluid column 13. The rarefaction below the balls 21 assists the pressure wave above these balls to insure seating thereof.

In addition, the wave-transmitting action of the acoustic valve means 14 permits a condition of substantial resonance to be obtained in the acoustic chamber 58, and it is believed to be new to pump fluid by use of an acoustic chamber on one side of the valve, in which a condition of approximate resonance is established by undulations transmitted to the other side of the valve. It is believed to be new, also, to establish substantial resonance on both sides of an acoustic valve.

An alternative means for discharging fluid, having advantages in efficiency and in facility of control, is shown in Figures 7 and 8. In this embodiment, the discharge opening is opened and closed in synchronism with the generating piston 25. A cam 60 is preferably mounted on the end of the shaft 31 to rotate therewith. In the plane of rotation of the cam 60 is preferably mounted a cylinder 61 within which moves a preferably hollow plunger 62. On the outer end of the plunger 62 is rotatably mounted a ball bearing 63, or other suitable wheel, adapted to

ride in engagement with the cam 60. The plunger 62 is forced outwardly into engagement with the cam 60 by a spring 64 acting between an outwardly-directed flange on the plunger 62 and a shoulder on the cylinder 61. Connected with the fluid chamber within the cylinder 61 is a fluid conduit 67 through which fluid is moved as the plunger 62 moves within the cylinder 61. It will be evident that, as the shaft 31 rotates, the rotation of the cam 60 causes the plunger 62 to move in and out of the cylinder 61.

The part of the vibration cycle at which the plunger 62 is moved inwardly by the cam 60 depends upon the angular orientation at which the cylinder 61 is fixed. Means are provided for varying the angular orientation of the cylinder 61 and comprises a stationary plate 68 having an arcuate slot 70 therein adapted to accommodate two screws 71 which pass through supporting lugs 72 on the cylinder 61. The cylinder 61 may be swung into any angle within a range of 180°, and nuts 73 may be tightened to retain the cylinder 61 in the selected angular position permitted by the slot 70. If it is desired to move the piston 62 inwardly during the other half of the vibration cycle, the cam 60 is removed from the shaft 31 and replaced at an angle differing by 180° from its former position. The cylinder 61 may then be moved to any position along the slot 70 for fine adjustment of the timing.

At the desired location for fluid discharge, which may, for example, be at the upper end of the fluid column 13 in the general neighborhood of the generating piston 25, a flanged discharge member 75 may be welded into the conduit 12. The discharge member 75 may have apertures 76 suitably located for the discharge of fluid from the well. The member 75 is preferably shaped to provide a shoulder 77 against which rests a valve seat 78. The valve seat 78 may be forced against the shoulder 77 by a member 79 which, in turn, is retained by a ring 81 which is screwed into the threaded outer end of the member 75. The member 79 is open over most of the periphery and is so located as not to interfere with the discharge of fluid through the apertures 76. The member 79 is centrally bored and provides a supporting bushing for the stem of a valve 82 adapted to seat on the valve seat 78.

Pressure of fluid in the fluid column 13 tends to close the valve 82 and, to open it, I provide fluid-operated means, as follows. Two stationary supporting members 85 and 86 may be mounted on the discharge member 75 and be connected at their outer ends by a member 87. Within this framework, a fluid cylinder 88 is supported by means of an adjustable bracket 90. Within the cylinder 88 are preferably located two pistons 91 and 92 separated from one another to form within the cylinder 88 a chamber 93. The fluid conduit 67 leading from the cylinder 61 connects with the chamber 93 so that, when fluid pressure is transmitted through the conduit 67 to the chamber 93, the pistons 91 and 92 tend to move apart. The piston 92 is connected to a rod 95 which is slidably supported in an end of the cylinder 88 and extends into contact with the end of the stem of the valve 82. The piston 91 is connected to a rod 97 which is slidably supported in the other end of the cylinder 88 and carries a spring abutment 98. A screw 100 passes through the frame member 87 in threaded engagement therewith and carries at its end a spring abutment 102 within which it can rotate. Between the spring abutments 98 and 102 is

placed a compression spring 104 which urges the piston 91 toward the piston 92. The compression of the spring 104 may be adjusted by screwing in or out of the screw 100.

When the high part of the cam 60 comes under the plunger 62, the plunger 62 is forced into the cylinder 61 and fluid is forced through the conduit 67 into the chamber 93. The pistons 91 and 92 tend to move apart by reason of this pressure but, generally, the force with which the valve 82 is held closed by pressure within the well is greater than the force exerted by the spring 104 and, consequently, only the piston 91 at first moves. The motion of the piston 91 away from the piston 92 continues until the force of compression exerted by the spring 104 equals the force with which the valve 82 is held on its seat. Any further pressure in the chamber 93 then causes the piston 92 to move also, whereupon the valve 82 is lifted from its seat and fluid from the fluid column 13 may flow out through the discharge apertures 76. It will be clear that the point in the rotation of the cam 60 at which the pressure in the chamber 93 is sufficient to open the valve 82 depends upon the initial state of compression of the spring 104, which may be adjusted by means of the screw 100 or through shifting of the adjustable bracket 90. When the cam 60 rotates around to where the plunger 62 is permitted to move outwardly and reduce the pressure in the chamber 93, the valve 82 will again close and will remain closed until the cam 60 once more forces the plunger 62 inwardly. By this means, then, I provide a discharge passage which is opened and closed with the same frequency as that of the generating piston 25. Moreover, it will be apparent that, by varying the angular orientation of the cylinder 61, I may cause the valve 82 to open at any selected part of the vibration cycle, and that, by adjustment of the compression of the spring 104, I may control the time interval during which the valve 82 is maintained open.

I have found that discharge of fluid from the fluid column 13 through the synchronized discharge valve may be obtained when the opening of the discharge valve is timed to occur at any part of the vibration cycle. The discharge of fluid and the efficiency of pumping are, however, found to be greater for some particular timing and duration of the discharge period relative to the vibration cycle, depending upon the location of the discharge outlet along the fluid column and other existing conditions. In each particular case, therefore, I preferably adjust the time interval during which the discharge valve is maintained open and, also, the timing of the opening of the discharge valve relative to the phase of the generating piston 25 in its vibration to secure the best results. One very satisfactory adjustment, which results in small energy dissipation, is that for which fluid discharge takes place during a portion of the vibration cycle at which the fluid pressure at the point of discharge is about equal to the mean fluid pressure throughout the cycle.

A very desirable system for pumping fluids containing dissolved or occluded gases is shown in Figure 9, in which the main conduit is indicated by the numeral 112, the main fluid column by the numeral 113, the acoustic valve by the numeral 114, and the generating means (shown only diagrammatically) by the numeral 115.

The acoustic valve means is best shown in Figures 9 to 12 and represents a construction

which can be used either in this embodiment or in the other embodiments of the invention. As shown, this acoustic valve includes a cap member 116 threaded, or otherwise secured, to the lower end of the conduit 112 and providing a plurality of apertures 117 surrounding a central aperture 117'. The upper end of each of the apertures 117, and, if desired, the aperture 117', is double-countersunk to provide intersecting conical surfaces 118 and 119 to provide a seat for a ball 121, conical surface 119 serving either as a portion of the seat or as a surface along which the ball may roll by gravity to come into a seating position.

Suitable means is provided for maintaining the balls 121 in the general vicinity of their seats, and particular advantages accrue from the use of a reflecting member 122 in this connection. This member may be clamped between a shoulder of the member 116 and the lower end of the conduit 112 at such elevation as to permit lifting of the balls while preventing removal thereof from the vicinity of the apertures 117. This reflecting member 122 presents a flat surface to a wave of condensation and serves as an excellent reflecting means therefor. Small openings 123 are provided therein for the conduction of fluid, these openings preferably being slightly disaligned with respect to the apertures 117 but communicating respectively with the zones in which the balls 121 are positioned. This member is shown as providing an opening 123' in alignment with the aperture 117', or, if this aperture is provided with a ball means, it will preferably be disaligned in accordance with the previous teaching. The member 122 can be made quite rigid or it can be made of a character to flex under the action of a condensation wave so that the central portion thereof moves in a manner to assist the pumping action.

In this embodiment of the invention, an acoustic chamber 130 is preferably provided below the acoustic valve 114 and serves a function similar to the acoustic chamber 58, previously described, though its construction is somewhat different. The chamber 130 is shown as being provided by a cylindrical member 131 extending from a position just above the acoustic valve 114 to a lower position removed substantially one quarter wave length from the valve, the lower end being closed by a member 132 which, if desired, may provide a small aperture 133 for purpose of removing from the chamber 130 sand or other material which may separate therein under the resonant conditions therein. This cylindrical member 131 may be retained in place by any suitable means, shown diagrammatically in Figures 9 and 10 as including arms 134 extending inward to the cap member 116. The diameter of the upper end of this cylindrical member 131 is larger than the external diameter of the cap member 116 to provide an annular inlet opening 135 through which fluid is admitted to the acoustic chamber 130 preparatory to movement through the acoustic valve means.

This acoustic chamber 130 assists in the pumping action and in the actuation of the acoustic valve means, as follows. When a condensation wave moving through the fluid column 113 reaches the reflecting member 122 to be violently reflected upward, a wave of rarefaction is established at a time corresponding to one half wave cycle later, as previously described, to permit upward flow of fluid through the acoustic valve. A portion of this rarefaction wave is transmitted

downward through the acoustic valve, through the now-opened check valves or through the apertures 117', to the chamber 130. This rarefaction moves downward through the fluid in the acoustic chamber, reaching the member 132 at a time corresponding to one quarter wave cycle later, being then reflected upward as a rarefaction which moves through the annular inlet opening 135 after the lapse of another equal increment of time. This annular inlet opening acts similarly to an open-ended organ pipe so that the rarefaction wave moving therethrough creates a pressure wave which moves downward in the chamber 130 to be reflected upward from the member 132 to reach the acoustic valve means at a time corresponding to one full wave cycle after the rarefaction in the main column creating this phenomena. This pressure wave at the lower end of the acoustic valve correspondingly assists the rarefaction generated at the lower end of the fluid column 113 in opening the valve. If the aperture 117' is not valved, the thus-generated rarefaction wave can be transmitted in part therethrough, even to a greater extent than if the ball valve is used to close this aperture.

Also, if the aperture 117' is not valved, as is usually preferable in this embodiment, a compression wave reaching the member 122 will be partially transmitted (though predominantly reflected) and the transmitted portion will move through the opening 123' and the aperture 117' to form a condensation wave in the acoustic chamber 130, which moves downward to be reflected by the member 132 and move upward as a condensation wave to be present below the acoustic valve at a time corresponding to one half wave cycle after the arrival of the downward-moving condensation wave in the fluid column 113. In other words, this upward-moving pressure wave in the acoustic chamber 130 reaches the bottom of the acoustic valve at a time when there exists above the valve a rarefaction created by reflection of the main pressure wave. Correspondingly, an auxiliary action is obtained by use of the acoustic chamber 130 assisting the operation of the acoustic valve means and assisting in the up and down motion of the balls 121.

In the embodiment of the invention shown in Figure 9, the upper end of the fluid column is curved so that the piston 138 of the generating means 115 moves upward (though still inward with respect to the fluid column) to create the pressure impulses or waves of condensation. This can be accomplished by use of a curved conduit 140, or suitable dome structure, the showing being merely diagrammatic for purpose of illustration. Likewise, the means for reciprocating the piston is indicated diagrammatically by the numeral 141 but, in practice, will comprise the eccentric means previously described, or other means for oscillating the piston or creating the desired undulations in the upper end of the column.

In this system, as in the embodiments previously described, the acoustic valve means 114 will be positioned adjacent a zone of maximum pressure variation and the length of the fluid column 113 will be a multiple of one half wave length, i.e., the acoustic valve means will be spaced from the generating means a distance which is one half wave length or a multiple thereof. Usually, this spacing will be at least one full wave length, and often more, in which instance excessive transient pressures, if they are found to develop in the system, can be relieved by a spring-loaded

valve 143 disposed adjacent a zone of maximum pressure variation along the conduit 112, as previously suggested.

In the embodiment of Figure 9, the discharge of fluid is from the extreme upper end of the curved conduit or hollow structure 140, thus removing from the main fluid column, along with the discharged fluid, any gases which may have separated therein, and thus preventing "gas lock" of the system. This is an important feature in pumping fluids containing gases which are liberated upon any substantial reduction in pressure below formation pressure, such reduction in pressure being common in any well-pumping system because of the reduction in static head toward the surface of the ground. The mean pressure on the fluid column 113 decreases toward the upper end, and if gases are liberated, the gas particles will tend to move to a zone of maximum velocity variation. They may remain there for a short interval of time before rather quickly moving upward to the next zone of maximum velocity variation. Eventually, however, they reach the curved conduit 140 and are removed with the fluid from the extreme upper end thereof through a discharge conduit 145. In pumping such gas-liberating fluids, the discharge may be somewhat intermittent, the proportion of gas being greater at one time than at another. Similarly, the amount of energy stored in the fluid column may vary, reducing during the time that any excessive amount of gas is being discharged, and increasing as soon as the excess gas has been expelled. Even if the discharge from the system is largely composed of gas for a short interval of time, the resonant conditions in the fluid column do not completely die down, though there will be less energy imparted to the system by the generating means because of the cushioning action of existing gases. These gases are removed from the extreme upper end of the system and, as soon as the presence of excessively large amounts of gas is corrected, the generating means will begin to store additional energy in the column and increase the amplitude of the pressure variations to effect further pumping. Depending upon the character of the fluid, the discharge through the conduit 145 may consist entirely of liquid, or may represent a relatively constant mixture of liquid and gas, or may represent a varying mixture of liquid and gas.

The discharge conduit 145 may be valved by any of the means heretofore described, but I prefer to extend this conduit, preferably slightly inclined, to a chamber 150 disposed a distance from the generating means approximately one quarter wave length, in which event the pressure in this chamber will be relatively constant and will substantially equal the mean pressure of the wave existing in the curved conduit 140. This chamber is preferably closed and any mixture of liquid and gases entering same near its lower end may separate predominantly into bodies of liquid and gas, indicated respectively by the numerals 151 and 152, this body of gas being compressible to reduce further any pressure variations in the chamber 150.

While the gas and the liquid can be separately removed from the chamber 150, I prefer to dispose a discharge opening 154 at such position as to discharge both gas and liquid from this chamber. A spring-loaded valve 156 is preferably employed at this point to maintain a higher mean pressure on the system and to prevent any return flow of fluid through the opening 154. This valve

156 discharges through a conduit 157 to a suitable gas separator 158, which may be of any construction known in the art. Here, the liquid and the gas separate into separate bodies 159 and 160, gas being withdrawn continuously or intermittently through a pipe 161 and the liquid being withdrawn through a pipe 162. If desired, a constant-level system can be employed, indicated generally by the numeral 163, to control the discharge of the liquid. The pressure in the gas separator 158 may be made substantially above atmospheric pressure by throttling the separate discharge of the gas and oil, or the pressure can be maintained close to atmospheric pressure, if desired.

In the embodiment shown in Figure 9, I have disclosed an advantageous method tending to overcome the presence of strong rarefaction waves in the upper end of the column by admitting fluid thereto in timed relationship with the generating means. For example, a pipe 170 may be connected to a port 171 which is uncovered by 20 or which, as suggested in Figure 9, can be disposed to be out of the zone of travel of the piston to communicate with the fluid column at all times. In at least the latter event, this pipe 170 will be equipped with a check valve 172 to prevent any discharge of fluid when the pressure in the column exceeds that in the pipe 173 to which the valve is connected. On the other hand, during periods of rarefaction in the curved conduit 140, fluid may flow from the pipe 173 through the valve 172 and the pipe 170 into the curved conduit. The reduced pressure at which this flow takes place is controlled by adjusting the spring-loading of the valve 172.

As disclosed in Figure 9, the pipe 173 may extend to the gas separator 158 to communicate with the body of liquid 159 therein. By such a system, a portion of the pumped fluid can be returned to the system and recycled through a portion thereof, namely, that portion of the curved conduit 140 between the pipe 170 and the discharge conduit 145, being ultimately discharged along with the pumped fluid rising in the main fluid column 113. Alternatively, fluid can be removed from a container 180 and thus drawn into the system, by closing a valve 181 in the pipe 173 and opening a valve 182. The container 180 may be open to the atmosphere or closed therefrom, depending upon the desired pressure therein, and the liquid therein may be maintained under pressure, if desired, which pressure can be substantially the same as that existing in the gas separator 158 if the upper end of the container 180 is connected to the body of gas 160.

Alternatively, the valves 181 and 182 can each be partially opened to supply to the curved conduit 140, during periods of rarefaction, a composite of the liquids in the gas separator and in the container 180. It is often advantageous to introduce in this manner a treating agent retained in the container 180 and which may be desirable for incorporation into the pumped fluid to assist in the separation of its constituents, the wave motion in the curved conduit 140 tending to mix this intimately with the fluid being pumped from the well. If desired, a treating agent can be used which has a deemulsifying action with respect to emulsions in the system, or this treating agent can be one which otherwise facilitates the pumping action or the steps subsequently

used in storing or processing the well-produced fluid.

The principle of operation of my pump is entirely different from ordinary pumps in which fluid is raised by suction of a piston moving in one direction and is ejected when the piston moves in the opposite direction. Such pumps cannot pump fluid against a suction head of more than atmospheric pressure, which limits such pumps in the pumping of water to a suction head of about 30'. In contrast to this, I have, with the pump of my invention, successfully pumped water against a suction head of several hundred feet. It is important to understand that, in the pumping system of my invention, the valve means 14, at the lower end of the fluid column in the disclosed embodiment, is not opened by reason of a reduced pressure induced by the upward movement of the piston 25 and transmitted throughout the fluid column to its lower end, but is opened by a decreased pressure at the valve means 14 which occurs during the rarefaction part of the vibration cycle following and, as a result of, the preceding positive pressure wave. This decrease in pressure occurring during the rarefaction part of the vibration cycle may, at the valve means 14, be many times the reduced pressure which could be induced by the upward movement of the piston 25.

In the case of ordinary well pumps using sucker rods extending the length of the well, it is common practice to employ tubing within the well casing, if for no other reason than to restrain the sucker rod from excessive lateral movement. With my system, no sucker rod is required and the tubing can also be dispensed with, the fluid being conducted by use of the well casing alone. A tubing may, however, be employed within the well casing to conduct the fluid, if it is so desired.

While I have disclosed my method and apparatus for pumping in connection with a well, and have mentioned liquids as examples of the pumped fluid, I do not intend my invention to be so limited. My invention may be applied to a wide variety of pumping problems other than those involving wells. My invention is applicable to the pumping of any fluid, the frequency of vibration of the acoustic generator preferably being adjusted in each case, as above-described, to result in a condition of approximate acoustic resonance in the fluid column. In my use of the term "acoustic," I intend it to pertain to elastic disturbances of any frequency, whether or not they are within the audible range. It will be understood that the parts of my apparatus herein-disclosed are merely illustrative, and that other means may be employed to perform their respective functions in the apparatus. Various changes and modifications in the method and the apparatus herein-disclosed may be made by those skilled in the art without departing from the spirit and scope of the invention defined in the appended claims.

This application is a continuation-in-part of my application, Serial No. 258,223, filed February 24, 1939.

I claim as my invention:

1. A method of pumping fluid along a fluid column of given length, which method includes the steps of: imposing a static pressure substantially above atmospheric pressure on all portions of said fluid column while transmitting through said fluid column asymmetrical waves comprising successive waves of condensation of large magni- 75

tude and intervening waves of rarefaction of an amplitude much less than said waves of condensation and while controlling the frequency of said asymmetrical waves in such manner as to maintain a condition of approximate acoustic resonance in said fluid column, in which condition there exists along said fluid column a zone of substantially greatest pressure variation; reflecting said waves of condensation substantially at said zone of greatest pressure variation to aid in creating rarefactions tending to equal in amplitude the amplitude of said condensation waves; admitting fluid to said column adjacent such zone of reflection during each rarefaction to aid in making the wave transmitted through said column asymmetrical; and discharging fluid from said column at a position spaced from the point of admission of said fluid to said column.

2. A method of pumping fluid from a first location to a second location through a connecting fluid column, which method includes the steps of: generating elastic positive pressure waves in said fluid column to the exclusion of equal-intensity intervening rarefactions while controlling the frequency of said waves in such manner as to maintain approximate resonance in said fluid column and while maintaining a mean pressure in all portions of said column and which mean pressure is substantially above atmospheric pressure; reflecting said positive pressure waves at said first location to create adjacent said first location a rarefaction following each reflection; admitting fluid into said fluid column at said first location during the succeeding rarefactions set up by said reflection of said pressure waves while precluding such fluid admission between such rarefactions; and discharging fluid from said fluid column at a position spaced from said first location.

3. A method of pumping fluid along a fluid column from a first location to a second location, which method includes the steps of: imposing a static pressure on all portions of said fluid column while transmitting pressure impulses through said fluid column from said second location to said first location and while preventing transmission of corresponding-intensity rarefactions through said fluid column to said first location to establish a wave that is so asymmetrical when plotted with respect to said static pressure as a base that such pressure impulses greatly exceed any rarefactions transmitted through said column; reflecting said pressure impulses from said first location toward said second location without substantial deformation of the wave front of the pressure impulses during such reflection to create at said first location rarefactions of sufficient intensity to admit additional fluid to said fluid column adjacent said first location; controlling the frequency of the transmitted pressure impulses with respect to the distance between said locations to establish in said fluid column a condition of substantial resonance; and withdrawing fluid from said fluid column at a position spaced from said first location.

4. A method of pumping fluid along a fluid column from a first location to a second location, which method includes the steps of: imposing a static pressure substantially above atmospheric pressure on all portions of said fluid column while transmitting pressure impulses through said fluid column from said second location to said first location and while preventing transmission of corresponding-intensity rarefactions through said fluid column to said first location by admitting a fluid to said fluid column near said second lo-

cation synchronously with the appearance of rarefactions at said second location and in an amount sufficient to substantially reduce the rarefactions which would otherwise occur; reflecting said pressure impulses from said first location toward said second location to create at said first location rarefactions of sufficient intensity to admit additional fluid to said fluid column adjacent said first location; controlling the frequency of the transmitted pressure impulses with respect to the distance between said locations to establish in said fluid column a condition of substantial resonance; and withdrawing fluid from said fluid column at a position spaced from said first location.

5. Apparatus for pumping fluid along a fluid column of given length, including in combination: means for generating acoustic vibrations in said fluid column at such frequency as to maintain a condition of approximate acoustic resonance in said fluid column, in which condition there exists in said column a zone of substantially greatest pressure variation; means for admitting fluid into said fluid column approximately at said zones of substantially greatest pressure variation; and means for discharging fluid from said column at an exit position removed an odd multiple of a quarter wave length from said zone of maximum pressure variation.

6. A combination as defined in claim 5, including means for throttling the flow of fluid from said fluid column at said exit position to build up a back pressure on said fluid column.

7. Apparatus for pumping fluid, comprising: a conduit containing a fluid column; an acoustic valve means at one end of said fluid column and providing a wave-reflecting surface; wave-generating means spaced along said column a distance of approximately a multiple of one half wave length from said acoustic valve means for generating high-amplitude pressure pulses and low-amplitude intervening rarefaction pulses to produce a highly asymmetrical wave train in said fluid column; means for maintaining in said fluid column a mean pressure from which said pressure pulses and said rarefaction pulses depart, the amplitude of said rarefaction pulses adjacent said wave-generating means being insufficient at the existing mean pressure to reduce the pressure in said fluid column to zero value, the asymmetrical waves being transmitted through said fluid column and said pressure pulses being reflected from said acoustic valve means to create thereadjacent and at a time corresponding to one half wave length thereafter a rarefaction of sufficient magnitude to admit an increment of fluid to said fluid column; and means for discharging fluid from said fluid column at a position spaced from the point of admission of said fluid thereto.

8. Apparatus for pumping fluid from a first location to a second location, comprising: a fluid column extending between said two locations; wave-generating means for generating pressure pulses and intervening rarefaction pulses in said fluid column, said means including means for reducing the amplitude of said rarefaction pulses to a value very substantially below the amplitude of said pressure pulses, the length of said fluid column being approximately a multiple of one half wave length of the wave generated by said wave-generating means; means for maintaining in said fluid column a mean pressure from which said pressure pulses and said rarefaction pulses depart; acoustic valve means at said first location and capable of opening and closing at a fre-

quency corresponding to the frequency of said wave-generating means to admit fluid into said fluid column at said first location, said acoustic valve means comprising means for reflecting said pressure waves at said first location in a manner tending to produce at said first location rarefactions of amplitude only slightly less than the amplitude of the reflected pressure pulses to reduce the pressure adjacent said acoustic valve means sufficient to admit a momentary flow of fluid into said column; and means for discharging fluid from said fluid column at a position spaced from said first location.

9. Apparatus for pumping fluid, including in combination: a conduit extending downward into a well and enclosing a fluid column, the upper end of said conduit comprising a hollow structure providing a portion in open communication with that portion of said conduit which extends into said well; a generating means for generating elastic vibrations, said generating means being in open communication with another portion of said hollow structure, said generating means being at an elevation below the upper end of said hollow structure; an acoustic valve means for admitting fluid to said fluid column in response to wave energy received from said generating means; and discharge means communicating with the upper end of said hollow structure and thus communicating with said fluid column at a position which is higher in elevation than said generating means, said discharge means removing from said fluid column the pumped fluid and any gases liberated during pumping.

10. Apparatus for pumping fluid, including in combination: a conduit enclosing a fluid column; a generating means communicating with said fluid column for generating elastic vibrations; an acoustic valve means for admitting fluid to said fluid column in response to wave energy received from said generating means; discharge means communicating with said fluid column at a position which is higher in elevation than said generating means for removing from said fluid column the pumped fluid and any gases liberated during pumping, said discharge means being positioned at the highest point of said fluid column; and a gas-separation means communicating with said discharge means for separating gas from the pumped fluid.

11. Apparatus for pumping fluid, including in combination: a conduit enclosing a fluid column; a generating means communicating with said fluid column for generating elastic vibrations; an acoustic valve means for admitting fluid to said fluid column in response to wave energy received from said generating means; discharge means communicating with said fluid column at a position which is higher in elevation than said generating means for removing from said fluid column the pumped fluid and any gases liberated during pumping, said discharge means being positioned at the highest point of said fluid column; a gas-separation means communicating with said discharge means for separating gas from the pumped fluid; and means for returning to said fluid column for re-discharge through said discharge means a portion of the fluid separating from said gas in said gas-separation means.

12. Apparatus for pumping fluid from a first location to a second location, comprising: a fluid column extending between said two locations; means generating elastic pressure waves in said fluid column at said second location, the length of said fluid column being approximately a mul-

tiple of one half wave length of said waves; an acoustic valve means at said first location and opening and closing at a frequency corresponding to said means for generating pressure waves to admit fluid into said fluid column during the succeeding rarefactions set up by reflection of said pressure waves at said first location; means for discharging fluid from said fluid column at a position spaced from the point of admission of fluid thereto; and a pressure-responsive relief valve disposed between said first and second locations approximately at a point along said fluid column in which pressure variations are a maximum, said relief valve offering sufficient resistance to flow to preclude discharge of fluid therethrough except at excessive resonant pressures.

13. A method of pumping fluid along a fluid column, which method includes the steps of: transmitting acoustic impulses through said fluid column to establish substantially a condition of resonance therein; admitting fluid to said fluid column at one position in timed relation with said acoustic pressure impulses; withdrawing fluid from said fluid column at another position; and introducing fluid into said fluid column between successive pressure impulses at a third position spaced from said position to mingle with the fluid of said fluid column and discharge therewith at said other position.

14. A method of pumping fluid from a lower entrance location to an upper exit location, which method includes the steps of: maintaining a column of fluid extending between said locations whereby the pressure head on said column increases toward said lower entrance location; building up a substantial superatmospheric pressure on all portions of said fluid column in addition to the pressure existing at any particular section due to the pressure head of the fluid thereabove to maintain the mean pressure in said column at a value considerably above atmospheric pressure; generating high-amplitude pressure impulses in said fluid column and transmitting these pressure impulses downward through said fluid column to said lower entrance location; reflecting said pressure impulses adjacent said lower entrance location without substantial deformation of the wave front of the pressure impulses to create a momentary rarefaction at said lower entrance location at a period of time corresponding to one half wave length after the reflection, said momentary rarefaction being of sufficient magnitude to reduce the internal pressure to a value below that existing outside said fluid column at said lower entrance location to admit an increment of fluid to said fluid column; and discharging fluid from said fluid column at a position above said lower entrance location.

15. A method of operating an acoustic valve for the intermittent passage of fluid therethrough, which method includes the steps of: maintaining constantly intercommunicating fluid columns on opposite sides of said valve; generating elastic vibrations in one of said columns; transmitting the elastic vibrations at least in part through said acoustic valve to the other of said fluid columns to establish secondary elastic vibrations in said second fluid column; and controlling the frequency of said elastic vibrations in said one column to maintain in said other column a condition of approximate resonance and to make said secondary elastic vibrations assist in the actuation of said acoustic valve.

16. Apparatus for pumping fluid, including in combination: a conduit enclosing a fluid column; 75

a substantially-flat reflecting surface traversing said fluid column; means for generating pressure impulses in said fluid column at a position approximately a multiple of one half wave length from said reflecting surface to establish a condition of approximate resonance in the intervening portion of said fluid column because of reflection of said impulses from said reflecting surface, said reflections creating succeeding rarefactions adjacent said reflecting surface to reduce the pressure within the fluid column adjacent said reflecting surface to a value sufficiently low to admit fluid thereto; and an acoustic valve means adjacent said reflecting surface and comprising a plurality of apertures communicating between the interior and exterior of said fluid column and a plurality of movable restricting means for said apertures, said movable restricting means being movable from a restricting position to impede escape of fluid from said fluid column to an open position admitting fluid through said apertures to said column, said movable restricting means being of sufficiently small mass to be rapidly oscillated between said restricting and open positions in step with said pressure impulses and intervening rarefactions existing adjacent said reflecting surface.

17. Apparatus for pumping fluid, comprising: a fluid column; means for generating acoustic vibrations in said column of such wave length as to resonate said column and produce a zone of maximum pressure variation therein; means responsive to said vibrations to admit fluid into said column; and means for discharging fluid from said column, said discharge means communicating with said fluid column at a point removed from said generating means a distance corresponding approximately to an odd multiple of a quarter wave length of the acoustic vibrations.

18. Apparatus for pumping fluid from an underground source thereof, comprising: a conduit enclosing a fluid column and extending downwardly from the earth's surface into communication with said underground source of fluid; means at the earth's surface for generating acoustic vibrations in said fluid column including a vibrating member having a face substantially normal to the axis of said column in contact with said fluid column, said member vibrating at such a frequency that the length of said fluid column is approximately a multiple of one half wave length of the acoustic vibrations set up in said fluid column; an inwardly-opening check valve means at the lower end of said fluid column; and means removed from the vibrating member by a distance approximately equal to one quarter wave length or odd multiple thereof for discharging fluid from said fluid column in the vicinity of the earth's surface.

19. Apparatus for pumping fluid, including in combination: a conduit enclosing a fluid column; walls defining an acoustic intake chamber also containing fluid; a uni-directional wave transmitter disposed between said acoustic intake chamber and said fluid column including a through aperture continuously establishing communication between said acoustic intake chamber and said fluid column; and means for generating elastic vibrations in said fluid column at such frequency as to establish substantially a condition of resonance in said acoustic intake chamber by undulations transmitted to said fluid in said acoustic intake chamber through said uni-directional wave transmitter.

20. Apparatus for pumping fluid, including in

combination: a conduit enclosing a fluid column; walls defining an acoustic intake chamber; an acoustic valve means between said fluid column and said acoustic intake chamber for conducting fluid from said chamber to said column while impeding a reverse flow of said fluid, said acoustic valve means including an aperture continuously establishing communication between said conduit and said acoustic intake chamber; and a wave generating means for flowing fluid from said intake chamber to said fluid column through said acoustic valve means and for establishing a condition of substantial resonance in said acoustic intake chamber to assist the flow of fluid through said acoustic valve means.

21. Apparatus for pumping fluid, including in combination: a fluid column; an acoustic valve means for admitting fluid to said fluid column when the internal fluid pressure adjacent the exit side of said acoustic valve means is lower than the external pressure of the fluid adjacent the entrance side of said acoustic valve means, said acoustic valve means including check valve means admitting fluid to said column but impeding a reverse flow of fluid and also including a constantly-open aperture extending therethrough; means for delivering elastic vibrations to said acoustic valve means to periodically reduce the fluid pressure on the exit side of said valve means below the fluid pressure on the entrance side thereof to move said check valve means and produce a flow of fluid therethrough; and acoustic means on the entrance side of said acoustic valve means and responsive to the elastic vibrations transmitted to said acoustic valve means for assisting the movement of fluid through said acoustic valve means.

22. Apparatus for pumping fluid, including in combination: a conduit enclosing a fluid column; an acoustic valve means for admitting fluid to said column; discharge means for discharging fluid from said fluid column; wave generation means for generating sound waves in said column for pumping fluid into said column through said acoustic valve means and thence along said conduit to discharge from said discharge means, the frequency of said wave generation means being such as to create substantially a condition of resonance in said fluid column; and auxiliary means for delivering fluid to the resonating fluid column during said pumping and during periods of rarefaction within said fluid column to mingle with the pumped fluid and be discharged therewith.

23. Apparatus for pumping, comprising: a fluid column; means for generating acoustic vibrations in said fluid column at one end thereof; acoustic valve means at the other end of said column adapted to admit fluid into said fluid column during periods of rarefaction adjacent said valve means; means for discharging fluid from said fluid column during a selected discharge period in each vibration cycle; and means including a pressure responsive device adjustable during operation for changing the duration of said discharge period and the phase of said acoustic vibrations at which said discharge period occurs.

24. Apparatus for pumping fluid, comprising: a fluid column; means for generating acoustic vibrations in said column including a vibrating member in contact with said fluid at one end of said column and adapted to be vibrated at such a frequency as to substantially resonate said column; means responsive to said vibrations to introduce fluid at the other end of said column;

means to discharge fluid from said column; and means to actuate said discharge means in timed relationship to the vibration cycle, said means including a cam driven in synchronism with said vibrating means, a follower arranged to be displaced periodically by said cam, means to shift the position of said follower relative to said cam while in motion, whereby the phase relationship between said follower and the vibrating means may be varied during operation, and an operative connection from said follower to said discharge means.

25. Apparatus as in claim 24 and including resilient means to close said discharge means; hydraulic means to open said discharge means; means to produce fluid pressure by the displacement of said follower to actuate said hydraulic means; and means to vary the amount of displacement necessary to open said discharge means.

26. Apparatus for pumping fluid, including in combination: a conduit enclosing a fluid column; a substantially flat reflecting member providing a reflecting surface extending transversely of said fluid column and occupying a substantial portion of the cross-sectional area of said column; means for generating pressure impulses in said fluid column at a position approximately a multiple of one half wave length from one side of said reflecting member to establish a condition of approximate resonance in the intervening portion of said fluid column because of reflection of said impulses from said reflecting surface, said reflections creating rarefactions adjacent one side of said reflecting member at a time corresponding to one half wave length thereafter, said rarefactions reducing the pressure within the fluid column adjacent said reflecting surface to a value sufficiently low to admit fluid therein; a valve means adjacent and on the other side of said reflecting member from said means for generating pressure impulses, said valve means providing a stationary element connected to said conduit and providing an opening, and a movable element movable with respect to said opening from a flow-restricting position to a flow-permitting position and vice versa; and means for transmitting said rarefactions to said valve means to operate same to admit fluid to said column.

27. A combination as defined in claim 17, in which said discharge means includes a fluid-discharge restriction disposed approximately a quarter wave length from a point of maximum pressure variation and providing sufficient restriction to the discharged fluid to increase the mean pressure throughout said fluid column to a value substantially above atmospheric pressure.

28. An acoustic valve for controlling the flow of fluid into a conduit, said valve including in combination: substantially flat wall means extending transversely of said conduit to provide a wave reflecting surface and being of an area somewhat less than the cross-sectional area of said conduit to provide a passage means for the conduction of fluid; and valve means on the opposite side of said wall means from said reflecting surface and adjacent said wall means for controlling the flow of fluid through said passage means, said valve means comprising a stationary means comprising fluid conducting means and a movable member engageable with said stationary means to impede flow of fluid through said fluid conducting means in one direction.

29. Apparatus for pumping liquid, including in

combination: a conduit enclosing a column of said liquid; an acoustic intake valve means for delivering liquid to said column when the pressure on the entrance side thereof is less than the pressure on the discharge side thereof; means for generating substantially a wave of reverberation at a position spaced along said liquid column a distance of substantially one half wave length from said acoustic intake valve means, said wave of reverberation comprising high-amplitude pressure pulses spaced from each other by rarefactions of an amplitude much less than the amplitude of said pressure pulses; means for imposing on said liquid column a sufficient mean pressure, from which said pressure pulses and said rarefactions depart, to prevent said rarefactions from exceeding the tensile strength of said liquid of said column; and means for discharging liquid from said column.

30. Apparatus for pumping fluid, including in combination: a conduit enclosing a fluid column; means for generating acoustic vibrations in said fluid column at one position; an acoustic valve means for admitting fluid to said fluid column at another position; means for discharging fluid from said fluid column; and means for throttling the flow of fluid from said fluid column to build up and maintain a back pressure on said fluid column and increase the mean pressure therein sufficient that the acoustic vibrations never reduce the pressure in said column to zero value.

31. In a fluid pumping system, the combination of: a fluid-filled conduit means; an acoustic valve means in said conduit means to divide said fluid into two columns respectively on opposite sides of said valve means, said acoustic valve means including aperture means continuously interconnecting said columns and through which acoustic energy imparted to one of said columns will be transmitted in part to the other of said columns and including movable valve means restricting fluid flow in one direction through said acoustic valve means while permitting less restricted fluid flow in the other direction; and means for imparting sonic energy to said one of said columns at such frequency as to establish substantially a condition of acoustic resonance therein, the length of said other column being such that the sonic energy delivered thereto through said acoustic valve means at said frequency will establish substantially a condition of acoustic resonance therein.

32. Apparatus for pumping fluid from a first location to a second location, comprising: a fluid column extending between said locations; means at said second location for generating waves of condensation, said generating means tending to form waves of rarefaction intervening said waves of condensation; means for admitting fluid to said column in timed relationship with such tendency to form waves of rarefaction to substantially reduce such tendency, whereby said generating means and said admitting means cooperate in establishing asymmetrical waves which move to said first location and comprising waves of condensation of substantially greater amplitude than intervening waves of rarefaction; acoustic valve means at said first location for reflecting the condensations transmitted thereto through said fluid column in a manner tending to create rarefactions of an amplitude substantially equal to the amplitude of such condensations, said acoustic valve means including valved passage means for admitting fluid to said column

6 during such rarefactions created by reflection of said condensations; and means for discharging from said fluid column the fluid entering same through said acoustic valve means and through 10 said admitting means.

33. A method of pumping fluid along a fluid column, which method includes the steps of: transmitting acoustic pressure impulses to said fluid column; admitting fluid to said fluid column at one position in timed relation with said acoustic pressure impulses; withdrawing fluid from said fluid column at another position; and introducing a fluid comprising a treating agent into said fluid column at a third position to mingle with the fluid of said fluid column and discharge therewith at said other position, said pressure impulses serving to mix said treating agent and the pumped fluid before they discharge from said fluid column.

20 34. Apparatus for pumping fluid, including in combination: a conduit enclosing a fluid column; walls defining an acoustic intake chamber; a uni-directional wave transmitter disposed between said acoustic intake chamber and said fluid column for admitting fluid to said column from said intake chamber, said uni-directional wave transmitter including an acoustic valve means impeding flow from said fluid column to said intake chamber but permitting flow from said intake chamber to said fluid column, said uni-directional wave transmitter including also an aperture openly communicating between said fluid column and said intake chamber and being of substantially smaller cross-sectional area than the cross-sectional area of said fluid column; and means for generating elastic vibrations in said fluid column at such frequency as to establish substantially a condition of resonance in said acoustic intake chamber by undulations transmitted thereto through said uni-directional wave transmitter.

35 35. Apparatus for pumping fluid, including in combination: a conduit enclosing a fluid column; walls defining an acoustic intake chamber communicating at one end with said conduit and providing an open end which openly communicates with the fluid to be pumped; a uni-directional wave transmitter disposed between said acoustic intake chamber and said fluid column for admitting fluid to said column from said intake chamber; and means for generating elastic vibrations in said fluid column at such frequency as to establish substantially a condition of resonance in said acoustic intake chamber by undulations transmitted thereto through said uni-directional wave transmitter, the distance between said open end and said uni-directional wave transmitter being substantially one-half of the wave length of said generated elastic vibrations in said fluid column.

40 36. Apparatus for pumping fluid, including in combination: a conduit enclosing a fluid column; walls comprising side and end walls defining an acoustic intake chamber; a uni-directional wave transmitter disposed between said acoustic intake chamber and said fluid column for admitting fluid to said column from said intake chamber; and means for generating elastic vibrations in said fluid column at such frequency as to establish substantially a condition of resonance in said acoustic intake chamber by undulations transmitted thereto through said uni-directional wave transmitter, the distance between said end wall and said uni-directional wave transmitter being substantially equal to one-quarter of the

wave length of said generated elastic vibrations in said fluid column, and said walls providing an opening communicating between said acoustic intake chamber and the fluid to be pumped at a position near said uni-directional wave transmitter.

37. A method of pumping fluid comprising the steps of: establishing a body of fluid extending from a first location to a second location; imparting pressure impulses to said fluid body at said second location to generate elastic positive pressure waves in said fluid body while maintaining a mean pressure on said fluid body in excess of 25 pounds per square inch; reflecting said positive pressure waves at said first location to create a rarefaction adjacent said first location following each reflection; admitting fluid into said fluid body at said first location only during the occurrence of said rarefactions; and discharging fluid from said fluid column at a position spaced from said first location and at a pressure in excess of said mean pressure.

38. A method of pumping fluid along a confined body of fluid, which method includes the steps of: generating sound waves in said body of fluid at a given position thus tending to establish in said fluid body positive-pressure waves with intervening rarefactions, while maintaining a high mean pressure in all portions of said body of fluid and which mean pressure is substantially above atmospheric pressure and while preventing rarefactions of intensity equal to said positive-pressure waves by introducing increments of fluid into said confined body at a point adjacent the position at which said sound waves are generated and timed with the appearance of rarefactions at said point whereby said increments of fluid are introduced into said confined body of fluid to substantially reduce the intensity of the rarefactions, the increments of fluid thus introduced joining with the fluid of said confined body; controlling the frequency of generation of said sound waves so as to maintain a condition of approximate resonance in said confined fluid body; and discharging fluid from said confined body of fluid at a position spaced from the point where said increments of fluid are introduced.

39. Apparatus for pumping fluid, including in combination: walls confining a body of fluid; an acoustic valve means for admitting fluid to said confined body of fluid; discharge means for discharging fluid from said confined body of fluid; wave generation means for generating sound waves in said confined body of fluid from pumping fluid into said confined body of fluid through said acoustic valve means and thence along said confined body of fluid to discharge from said discharge means, the frequency of said wave generation means being such as to create substantially a condition of resonance in said confined body of fluid; and auxiliary means for delivering fluid to the resonating confined body of fluid during said pumping and during periods of rarefaction within said confined body of fluid to mingle with the pumped fluid and be discharged therewith.

40. Apparatus for pumping fluid, including in combination: means forming a sonic chamber adapted to contain a confined body of fluid under compression; a sound wave generator for generating acoustic vibrations in said confined body of fluid at such frequency as to establish substantially a condition of standing-wave resonance therein whereby the pressure at one position in said confined body of fluid varies cyclically to increase when a wave of condensation is adja-

cent said position and to decrease when a wave of rarefaction is adjacent said position; an intake valve adjacent said position for admitting additional fluid to said confined body of fluid when a

5 wave of rarefaction is adjacent said position and for impeding flow of fluid from said confined body of fluid when a wave of condensation is adjacent said position; and means for discharging fluid from said confined body of fluid, said last-
10 named means including a restricted orifice disposed a distance from said sound wave generator corresponding to an odd multiple of one quarter wave length of said acoustic vibrations for restricting the discharge of fluid sufficient to build up a high mean pressure throughout said confined body of fluid of at least 25 pounds per square inch.

41. Apparatus for pumping fluid, including in combination: means forming a sonic chamber
20 adapted to contain a confined body of fluid under compression; a sound wave generator for generating acoustic vibrations in said confined body of fluid at such frequency as to establish substantially a condition of standing wave resonance
25 therein whereby the pressure at one position in said confined body of fluid varies cyclically to increase when a wave of condensation is adjacent said position and to decrease when a wave of rarefaction is adjacent said position; an intake valve adjacent said position for admitting additional fluid to said confined body of fluid when a wave of rarefaction is adjacent said position and for impeding flow of fluid from said confined body of fluid when a wave of condensation
30 is adjacent said position; and a back-pressure valve for discharging fluid from said confined body of fluid and for maintaining a high mean pressure throughout said confined body of fluid of at least 25 pounds per square inch, said back-
35 pressure valve including relatively movable members defining a discharge orifice, and means for resiliently urging said members toward closed position to restrict the discharge of fluid from said confined body of fluid and establish said high mean pressure therein.

42. A combination as defined in claim 41, in which said back-pressure valve is spaced from said sound wave generator a distance, measured along the intervening fluid, corresponding substantially to an odd multiple of one-quarter of the wave length of the waves in said intervening fluid.

43. Apparatus for pumping fluid, including in combination: means forming a sonic chamber
55 adapted to contain a confined body of fluid under compression; a sound wave generator for generating sound waves in said confined body of fluid at such frequency as to establish substantially a condition of standing wave resonance in said body of fluid and to establish cyclically recurring pressure pulses and rarefactions adjacent said sound wave generator; means adjacent said sound wave generator for admitting additional increments of fluid to said confined body of fluid synchronously with the appearance of rarefactions adjacent said sound wave generator and in a manner tending to absorb said rarefactions, said means including a valve means opening to admit said increments of fluid to said confined body of fluid but closing to prevent substantial reverse flow; and means providing a restricted fluid-discharge orifice spaced from said sound wave generator a distance substantially corresponding to an odd multiple of one-quarter of the wave length of the sound waves in said confined

body of fluid for discharging fluid therefrom and imposing therewith a mean pressure of at least 25 pounds per square inch.

44. Apparatus for pumping fluid, including in combination: means forming a sonic chamber adapted to contain a confined body of fluid under compression; a sound wave generator for generating acoustic vibrations in said confined body of fluid at such frequency as to establish substantially a condition of standing-wave resonance therein whereby the pressure at one position in said confined body of fluid varies cyclically to increase when a wave of condensation is adjacent said position and to decrease when a wave of rarefaction is adjacent said position; an intake valve adjacent said position for admitting additional fluid to said confined body of fluid when a wave of rarefaction is adjacent said position and for impeding flow of fluid from said confined body of fluid when a wave of condensation is adjacent said position; a tuned intake pipe extending from said valve for supplying fluid thereto preparatory to entry into said confined body of fluid through said intake valve, the wave motion in said confined body of fluid being transmitted in part through said intake valve to the fluid in said intake pipe and the intake pipe being of such length relative to the thus-transmitted wave motion that the fluid in this intake pipe will resonate because of the thus-transmitted wave motion to establish a condition of resonance in said intake pipe to aid in the flow of fluid through said valve into said confined body of fluid; and fluid-discharge means for discharging fluid from said confined body of fluid in a manner to build up a high mean pressure in said confined body of fluid of at least 25 pounds per square inch.

45. Apparatus for pumping fluid, including in combination: means forming a sonic chamber adapted to contain a confined body of fluid under compression; a sound wave generator for generating acoustic vibrations in said confined body of fluid at such frequency as to establish substantially a condition of standing-wave resonance therein whereby the pressure at one position in said confined body of fluid varies cyclically to increase when a wave of condensation is adjacent said position and to decrease when a wave of rarefaction is adjacent said position; an intake valve adjacent said position for admitting additional fluid to said confined body of fluid when a wave of rarefaction is adjacent said position and for impeding flow of fluid from said confined body of fluid when a wave of condensation is adjacent said position, said intake valve including means defining a plurality of apertures communicating between the fluid in said confined body and fluid exterior of said confined body, and a movable restricting means for each aperture, said movable restricting means being movable from a restricting position to impede escape of fluid from said confined body to an open position admitting fluid through said apertures to said confined body, each of said movable restricting means being of sufficiently small mass to be rapidly oscillated between said restricting and open positions in step with the cyclic variation in pressure adjacent said intake valve; and means for discharging fluid from said body of fluid and including a restricted orifice for restricting the discharge of said fluid sufficient to 35 build up a high mean pressure throughout said confined body of fluid of at least 25 pounds per square inch.

ALBERT G. BODINE, JR.

CERTIFICATE OF CORRECTION.

Patent No. 2,355,618.

August 15, 1944.

ALBERT G. BODINE, JR.

It is hereby certified that error appears in the printed specification of the above numbered patent requiring correction as follows: Page 6, second column, line 4, strike out the word "of" after "out"; page 10, first column, line 24, claim 5, for "zones" read --zone--; line 26, same claim, after "removed" insert --approximately--; page 11, first column, line 19, claim 13, after "acoustic" insert --pressure--; page 14, first column, line 54, claim 39, for "from" read --for--; page 15, first column, line 2, claim 43, for "therewith" read --therewithin--; and that the said Letters Patent should be read with this correction therein that the same may conform to the record of the case in the Patent Office.

Signed and sealed this 10th day of October, A. D. 1944.

Henry Van Arsdale
